(57) **CLAIM**

The ornamental design for an infant bib, as shown and described.

DESCRIPTION

FIG. 1 is a frontal perspective view of an infant bib of our new design.

FIG. 2 is a front elevation view of the infant bib of our new design.

FIG. 3 is a rear elevation view of the infant bib of our new design.

FIG. 4 is a right side view of the infant bib of our new design.

FIG. 5 is a left side view of the infant bib of our new design.

FIG. 6 is a top plan view of the infant bib of our new design.

FIG. 7 is a bottom plan view of the infant bib of our new design; and,

FIG. 8 is a frontal perspective view of the infant bib of new design folded for storage.

1 Claim, 6 Drawing Sheets
